DEVICE FOR MAKING ONESELF A TIE KNOT

Jules Ferdinand Ramas, Chatou, France

Application September 1, 1936, Serial No. 98,952
In France September 12, 1935

1 Claim. (Cl. 2—155)

It is known that with double collars, particularly stiff collars, it is difficult to put one's tie on correctly, whether it is a so-called "sailor-knot" tie, or a "butterfly" bow, so that numerous "ready made bow" devices and "systems" have been devised on which the user himself makes a knot or bow, but which, among other inconveniences, are generally rendered obvious, either by their uniform stiffness, or even by their partially apparent armature.

With the usual tie, even by trying to make the knot at the crossing point of the double collar and at its middle portion, this knot is usually formed at a certain distance and often on one side, so that for placing it correctly in position, it is necessary to pull on the ends of the tie; but the latter, particularly under a stiff double collar, slides but with very great difficulty, and, as soon as the knot has been tightened, it is no longer possible to modify its shape and position. Moreover, the knot having a tendency to loosen, the user is frequently compelled to retighten it. All these efforts strain the fabric of the tie, they distort it and determine its rapid wear; on the other hand, the collar is easily soiled or crumpled during these operations. Finally, whether the collar is stiff or soft, it is not unnecessary, particularly in summer to add about the neck a thickness of fabric to the two or three thicknesses which already exist, according as the shirt is provided with a collar integral with the same, or with a removable collar.

The present invention is adapted to remedy, for the stiff or soft double collar, to the inconveniences of the "ready made" bow, of the devices called "systems", and also of the usual tie.

In fact, it allows the user himself to tie the knot (sailor knot or butterfly bow, etc.) completely outside the collar, and, consequently, without the least difficulty, then to easily place it in correct and final position: once adjusted, the tie cannot become undone or get out of place. Moreover, it has absolutely the appearance of a normal tie perfectly tied, this constituting an essential advantage.

The invention substantially consists in forming the tie knot by means of a very simple auxiliary device constituted by the combination of two rings and of a resilient bond connecting them, and adapted to be passed around the neck, between the two thicknesses of the collar; the knot is made between the two rings and the elastic string holds this knot exactly in the right position.

In order that the invention may be clearly

understood, various forms of carrying the same into practice are illustrated in the accompanying drawings, given by way of example only, and in which:

Fig. 1 is an elevation of the new device.

Figs. 2 to 5 illustrate rings of various shapes.

Figs. 6 and 7 show a modification.

Figs. 8, 9 and 10 show how a sailor knot can be formed on the new device.

As illustrated in the drawings, the new device substantially comprises two rings *a* connected by an elastic bond *b*.

These rings can be closed or slotted. Their shape is variable, as they can be round (Fig. 2), oval (Fig. 3), of pear shape (Fig. 4), of yoke shape (Fig. 5), etc. In any case, they can be provided with a recess *c* for the bond or string *b* connecting them.

The said rings are made either of metal, or of any other material allowing the tie to easily slide.

The bond *b* can be a string or twist made of any material, but a resilient material: rubberized fabric, rubber covered with a fabric or encased rubber, metallic spring, etc.

The rings are passed in loops *d* at the ends of the elastic twist *b* (Fig. 1), or they are freely threaded on the twist which is closed on itself, as shown in Fig. 6.

In the latter case, upon use, the twist is folded back on itself, as illustrated in Fig. 7. This arrangement of Figs. 6 and 7 has the advantage of distributing the wear and strain throughout the length of the twist, instead of concentrating them at definite points.

The tie used (sailor knot or bow, etc.) is an ordinary tie, but the part corresponding to the neck portion is shorter than in the usual tie, to the extent of about 10 to 20 centimeters, since on a great part of the neck portion the tie proper is replaced by the elastic twist. Moreover, on the market can already be obtained, at least concerning the sailor knot tie, shortened ties to be used with "systems" which are perfectly suitable for the subject-matter of the invention.

For forming the tie knot, the tie is first passed in the rings *a* (Fig. 8), the short end *e* of the tie extending forwardly from one of the rings, and the long end *f* extending from the other ring, the right side of the tie being on the top. The whole is placed on the collar, as shown in Fig. 8.

The sailor knot is made as usual, except that the long end, after having formed the loop *g* constituting the body of the knot (Fig. 9), is passed behind the portion *h* which is located be-

tween the two rings, so as to enclose this portion *h* in the knot.

Fig. 9 shows the portion *i* of the long end which covers said portion *h* and extends in the loop of the tie *g*. Owing to this manner of tying the tie, the new device gives the impression of a usual tie, this constituting one of the essential features of the present invention.

Once the knot has been made outside the collar, a first adjustment of the neck portion can be effected, if necessary, by pulling upon the under short end *e*, the device and the tie then occupying on the collar the position shown in Fig. 9. Then the device is slipped under the collar *j*, by simultaneously using the thumb and index of each of the two hands for slightly pulling upon the rings and inserting them under the collar, this being very easily effected owing to the resiliency of the system; then, starting from each ring, the thumb is moved along the twist towards the rear portion of the collar; the twist is thus very easily pushed under the collar. The tie is then finally adjusted as for an ordinary tie, but with much greater facility, as the tie responds to the slightest action of the fingers. By pulling upon the under short end *e*, the tension of the twist is adjusted, and by pulling upon the other end *f*, the knot is shaped to one's desire.

The tie once in position appears as shown in Fig. 10.

For removing the tie, the knot can be undone as for an ordinary tie and tying it again when the tie is again to be used. But it is much more convenient to simply disengage the tie from the collar by simultaneously pulling upon the rings with the thumb and index of each hand, or more simply by gently pulling at the same time on both ends *e* and *f*: then, owing to the elasticity of the twist, the tie is passed over the head and it is removed. For putting the tie on again, the reverse operation is effected, as if a

ready made bow was used; but, in the present case, the knot is made by the user himself and can be easily readjusted, with the desirable sturdiness and according to the user's taste.

Whether the knot is remade every time, or 5 whether it is maintained ready made, by means of the device forming the subject-matter of the invention, the time necessary for putting on the tie is in any case less than with all previously existing devices, this representing an appreciable saving of time.

It is particularly with the stiff double collar that the new device is most advantageous, owing to the difficulties encountered, as above stated, for causing a tie to slide under such a collar, 15 but it is to be understood that with a soft collar the new system is applicable in the same conditions.

The invention is applicable not only to the "sailor knot" tie, but also to all the other ties 20 with which a knot is made by the user himself; if need be, ties of normal length might even be employed by neutralizing the excess of length of the neck portion by passing several times between the rings.

The arrangements described above are given by way of example only, the forms, materials and details of execution can be varied so as to adapt themselves particularly to the various shapes of collars and kinds of ties approved by fashion, and 30 this without departing from the scope of the invention.

What I claim as my invention and desire to secure by Letters Patent is:—

Device for making oneself a tie knot outside 35 the collar and subsequently allowing to place it in position, comprising two loops in which the two ends of the tie can be passed and caused to slide, and a double elastic bond in which the two loops are freely engaged.

JULES FERDINAND RAMAS.
